RUBBER LINED METAL BARREL

Claude S. Beldin, Yeadon, Pa., assignor to Pennsylvania Salt Manufacturing Company, Philadelphia, Pa., a corporation of Pennsylvania

Application April 19, 1933, Serial No. 666,792

3 Claims. (Cl. 220—63)

Objects of the present invention are to provide a rubber lined metal barrel or container in which the rubber lining is not subject to rupture by pressure of gas generated between it and the barrel due to leakage or seepage of fluid that attacks the metal; in which the rubber lining is readily removable and replaceable; in which there is no tendency for the lining to fall into or out of the barrel; in which existing types of metal barrels can be employed without other alteration and fitting than may be readily done by unskilled labor and without the employment of tools other than a wrench; and in which the metal barrel can be protected from the corrosive action of any of the contents of the barrel that pass through the lining. In other words, the object is to provide a metal barrel or container possessed of all the advantages of a rubber lining and free from the defects that have heretofore been inherent in such articles. Other objects of the invention will appear from the following description.

To these and other ends hereinafter stated, or appearing, the invention, generally stated, consists in a metal barrel or container having a roll at its open end, and having a rolling (in the sense of turned over or down with the effect of a roll) loose rubber lining conforming to the surface of the open end of the barrel and providing a skirt or lip hugging the outside surface and extending towards the bilge. The fit between the part of the barrel near its open end and the rolling part of the lining serves to maintain a partial vacuum between the barrel and its detached rubber lining, and also provides a vent for any gas that may be present or generated between the barrel and lining. This fit also serves to prevent the lining from falling into or out of the barrel. The invention also comprises the combination with a loose rubber lining of, a clamping ring overlying the turned down or rolling part of the skirt or lip of the lining, and encircling and clamping the barrel and provided with ears, and screw clips or hooks for holding a rubber lined cover onto the barrel and onto the rolling part of the lining.

The invention also comprises the improvements to be presently described and finally claimed.

In the following description reference will be made to the accompanying drawing forming part hereof and in which

Figure 1 is an elevational view, partly in section, of a barrel embodying features of the invention.

Fig. 2 is a top or plan view of the same.

Fig. 3 is a sectional view drawn to an enlarged scale and illustrating features of the invention, and

Figs. 4 and 5 are similar views illustrating modifications.

In the drawing 1 is a metal barrel having a roll 2 at its open end. 3 is a loose lining of rubber or rubberlike material, and it is a rolling lining in the sense that it is turned over or down with the effect of a roll as at 4, and it conforms to the surface of the roll 2, and it provides a skirt or lip 5, which hugs the outside of the barrel and extends towards the bilge. The rolling portion 4 of the lining is molded and vulcanized to embrace and cling to the roll 2 of the barrel and clings to its face. Between the confronting and unconnected faces of the lining 3 and barrel 1, there may be interposed a substance or material which neutralizes any of the contents of the barrel that may leak or seep through the rubber lining. For example, the lining or liner 3 may be treated with powdered lime in the event that the contents of the barrel be of acid character.

There is a dished metal lid or cover 6 lined permanently with rubber 7, which is attached to it. The rubber 7 is shown in Fig. 3, but is omitted from Figs. 4 and 5, for the sake of clearness. No novelty is claimed for the cover.

There are hooks 8 connected with the barrel, and they serve to overlie the rim of the cover and hold it down onto the rolling part 4 of the loose barrel lining 3, and also as a means for releasing the cover for removal. The hooks 8 may be variously attached to the barrel 1. Referring to Figs. 1, 2 and 3, this is accomplished by means of a clamping ring 9 having a tension bolt 10 between its ends and provided with perforated ears 11 through which the threaded shanks of the hooks extend and are engaged by nuts 12. The clamping ring overlies the skirt or lip 5 of the lining 3 and the roll 2 of the barrel constitutes an abutment for it. Evidently the clamping ring can be applied to any standard barrel without the use of tools other than a wrench for tightening the bolt 10.

As shown in Figs. 4 and 5, the ears 11^a are welded to the outside of the barrel, and in Fig. 4 they are arranged below and clear of the skirt 5 of the lining, whereas in Fig. 5 they are arranged underneath the skirt of the lining. In Fig. 5 the hooks are constructed in the manner described in connection with Fig. 3. In Fig. 4 the hooks are pivoted to the ears and are provided with long bills 13, so that they have a

spring action in respect to the rim of the cover or lid.

In use the close adherence of the rolling rubber lining to the outside surface of the roll of the barrel or container, prevents the lining from falling out of or into the barrel, and it also serves to maintain a partial, but substantial, vacuum between the lining and barrel, and it performs the further function of permitting of the escape of gas if any is generated between the barrel and lining, for example, by the corrosive action of any of the contents of the barrel that might leak or seep through the lining. To further explain, if the lip or skirt 5 be turned up and the barrel filled with liquid, air is driven out from between the barrel and lining and then the lip or skirt is turned down. Upon removal of the liquid from the barrel, air may not reenter between the barrel and the lining, because of the sealing effect of the close adherence of the lining to the outside of the rolled lip of the container or barrel. Similarly when the skirt is turned up, gas, if any is present or trapped, may escape from between the barrel and lining. The close fit between the outside of the barrel and rolling part of the lining prevents the lining from shifting, which, if it occurred, might result in tearing the lining. Since the rubber lining is not permanently secured to any part of the barrel, it may be readily removed and inspected and, if necessary, repaired and returned or replaced by another lining.

The word "barrel" is used as inclusive of containers which may not be strictly barrels, and the thickness or gauge of the metal may be compara-

tively thick, and such as meets the requirements of the Interstate Commerce Commission.

It will be obvious to those skilled in the art to which the invention relates that modifications may be made in details of construction and arrangement and matters of mere form without departing from the spirit of the invention which is not limited to such matters or otherwise than the prior art and the appended claims may require.

I claim:

1. A full open head metal barrel having at its open end an out-turned roll integral with the wall of the barrel, and having an imperforate rolling loose rubber lining conforming to and in contact with the exterior surface of the roll and disconnected from the roll and providing below the roll a skirt detached from and in contact with and by its elasticity hugging the outside surface of the curved wall of the barrel and extending towards the bilge.

2. A metal barrel having a full open head and a roll chime and inside and outside curved surfaces and provided with a loose imperforate rubber lining having a fold arranged over and hugging the roll chime, and the inside surface of the fold contacting with the inside and outside curved surfaces of the barrel and providing a tension fit over the chime of the barrel.

3. A metal barrel having a full open head and a chime and provided with a loose rubber lining having a fold in which the chime of the barrel is enclosed and which hugs the chime and provides a tension fit which retains the lining in place in the absence of a lid.

CLAUDE S. BELDIN.
